[57] CLAIM

The ornamental design for a dual closure container, as shown and described.

DESCRIPTION

FIG. 1 is an elevational view of a dual closure container showing my new design;

FIG. 2 is a top plan view;

FIG. 3 is an elevational view looking from the left of FIG. 1;

FIG. 4 is a bottom plan view;

FIG. 5 is a view showing the side opposite that seen in FIG. 2;

FIG. 6 is a view showing the side opposite that seen in FIG. 3;

FIG. 7 is a perspective view; and,

FIG. 8 is an exploded perspective view thereof.
